WELDED BOLSTER CENTER FILLER

John Christiansen, Berwick, Pa., assignor to
American Car and Foundry Company, New
York, N. Y., a corporation of New Jersey

Application June 6, 1942, Serial No. 446,071

9 Claims. (Cl. 105—414)

This invention relates in general to railway car underframes and in particular to that part of the underframe known as a bolster center filler.

In the past practically all railway cars have been built with cast steel bolster center fillers which had to be machined and then secured in position. Such center fillers were extremely heavy and in recent years there has been a trend toward the use of fabricated parts in order that the weights of the cars might be reduced. Further, in times of national emergency such as now exists it is almost impossible to secure cast steel for railway car use. It is an object, therefore, of the present invention to provide a welded bolster center filler which may be fabricated from small rolled metal shapes and plates.

A further object of the invention is the provision of a welded bolster center filler which may be fabricated as a unit and applied to the car in any suitable manner but preferably by riveting, thus permitting ready installation, repair and replacement.

A still further object of the invention is the provision of a welded bolster center filler having the parts made of rolled plates and shapes so arranged and attached to the center sills as to produce a plurality of exceptionally strong parts of substantially closed box section.

A yet further object of the invention is the provision of a welded bolster center filler which may be fabricated and applied to the car in much the same manner as the cast steel fillers are now applied, thus permitting the customary procedure to be used in construction of the car.

These and other objects of the invention will be apparent to persons skilled in the art from a study of the following description and accompanying drawing, in which

Figure 1 is a partial plan and partial sectional view showing the improved bolster center filler and adjacent parts of the underframe;

Fig. 2 is a sectional view taken substantially on line 2—2 of Fig. 1;

Figs. 3 and 4 are sectional views taken substantially on lines 3—3 and 4—4 respectively of Fig. 2;

Fig. 5 is a perspective view of one of the center sill tie plates forming part of the center filler;

Fig. 6 is a perspective view of the base plate, and

Fig. 7 is a perspective view of one of the main members forming the bolster center filler.

Referring now to the drawing in detail, it will be seen that the bolster center filler has been applied to a car having standard AAR center

sills, these sills being formed of special Z sections having relatively thick short flanges 2, webs 4 and thinner, longer flanges 6. The thinner, longer sections are welded together, as is customary, to give an inverted channel form center sill having outwardly directed bottom flanges. Near each end of the center sills the car bolsters are attached and these are formed, in the present case, of spaced bolster plates having webs 8, bottom flanges 10, top flanges 12 and inner end flanges 14. The bottom flanges 10 is pressed upwardly, as clearly shown in Figs. 3 and 4, to clear the bottom flange of the center sill and permit the major portion of the bottom flange to be directly secured to the bolster bottom cover plate 16. This bolster bottom cover plate rests upon and has secured thereto the center bearing 18 which may be of any suitable form and construction. The bolster diaphragm plates are also connected together, as is customary, by means of rivets or other securing devices extending through the top flanges 12 and through the top bolster cover plate 20. Since each center bearing must transmit at least one-half of the entire carload to the supporting trucks, it is necessary that an extremely strong center filler be used which is capable of transmitting the load and preventing any distortion of the center sills by the car body bolsters.

The center filler, as clearly shown in the drawing, is formed with what may be termed main filler members which are of special Z section and are positioned with the short thick flange 30 disposed to form the top portion, while the webs 32 are located vertically and the thinner, wider flanges 34 are disposed to form the lowermost portion of the filler. As applied the thinner, wider flanges 34 underlie and are directly attached to the shorter, thicker flanges 2 of the center sill, while the webs 32 are disposed in parallel spaced relationship to the webs 4 of the center sills. The narrow, thicker flanges 30 of the main filler members are disposed substantially horizontal and in direct contact with the upper flange portions 6 of the center sills to which they are attached. In other words, the main members of the center fillers are so positioned as to form an inverted channel member secured within the inverted channel form center sill and with the webs in spaced relation. In order to reinforce the inverted channel member of the center filler, opposed M-shaped plates are provided having the legs 36 welded to the webs 32 of the filler member and having the apices welded together as at W. In order to better accommodate the king pin con-

necting the car body and truck together, the central portion of these M-shaped plates is curved as at 38. In this manner the webs 32 of the inverted channel filler member are prevented from being distorted by a triangular shaped reinforcement formed by the legs of the M-shaped plates. As most clearly shown in Fig. 7 the webs of the Z sections forming the inverted channel center filler member are coped out as at 40 to receive tie plates 42, shown in perspective in Fig. 5. 10 These tie plates are formed with end flanges 44 pierced as at 46 to receive suitable securing means such as rivets 48. The bottom edge of the central portion of the tie plates is formed with a slight extension 50 adapted to fit between the lower portions of the inverted channel filler member and of such a length as to permit their direct attachment to a base plate 52 shown in perspective in Fig. 6. The central portions of the tie plates are welded or otherwise secured directly to the coped out portions of the Z members forming the inverted channel filler, all as clearly shown in Fig. 1. These tie plates thus mutually tie together the center sill webs and the webs of the inverted channel filler member. In order to provide a good connection and support for the center bearing, the base plate 52 is attached to the extended part 50 of the tie plates and extends outwardly through and is pierced as at 54 to receive suitable securing means 56. This base plate bears upon the lower ends of the M-shaped guide plates and is formed with stiffening corrugations 58 projecting upwardly between the webs 32 of the inverted channel filler member. The side edges of this base plate are beveled, as clearly shown in Figs. 3 and 4 in order that a good weld may be secured between the base plate and the lower portions of the webs of the inverted channel member. The base plate is provided with a central opening 60 adapted to receive the king pin and the edges of this opening are welded to the bottom edges of the M-shaped pin guide plates wherever possible. It will be seen from the preceding that the tie plates and inverted channel filler member, together with the base plate and car center sill, form three substantially closed box section portions directly above the center bearing, with the central box section internally braced by means of the M-shaped pin guide plates.

The center filler may be assembled in various ways dependent upon shop practice but it is preferred to assemble the prepared parts upon a jig and bring the pre-fabricated center filler to the car underframe for attachment thereto. In following this procedure the prepared Z section elements are placed in proper position on the jig and the tie plates fitted into the coped out areas and securely welded in place thereby tying the Z elements together and forming the inverted channel member closed at its ends by the tie plates. The M-shaped guide plates are next welded together and inserted between the webs of the inverted channel member and securely welded to the webs. With the M-shaped plates in position the base plate may now be securely attached as described, thus substantially closing the central box section area of the filler. The center filler is now practically complete and is assembled on the car by inserting between the center sill webs and fastened in place by driving the rivets or other securing means 48, thus fastening the center filler and bolster to the center sill. Next the rivets or other securing means 56 may be driven, thereby firmly connecting together the center filler, bolster bottom cover and center plate. If

fabricated and assembled in this manner the projecting ends of flanges 30 of the filler member may be welded to the top portion of the center sill. It may be desirable in some cases, however, 5 to more securely tie the flanges 30 of the inverted channel member to the top portion of the center sill, in which case the base plate 52 will not be applied until after the center filler is attached to the underframe and the flanges 30 securely welded as shown in Fig. 3. Regardless of the manner 10 of assembling and attachment, it will be seen that an extremely strong center filler is provided which cooperates with the center sills to form closed box sections over the center plate. It will also be seen that the center filler is securely attached to the center sills by rivets and welds, thereby developing the full strength of the materials forming the filler.

While the center filler has been described more or less in detail, it will be obvious to persons skilled in the art that various modifications and rearrangements may be made without departing from the scope of the following claims which define my invention.

25 What is claimed is:

1. In a car underframe including an inverted channel center sill having spaced apart webs, a bolster center filler comprising an inverted channel member having the webs and top portion thereof arranged within the center sill with the top portion directly connected to the center sill and the web portions thereof spaced from the center sill webs, means forming a king pin guide and joining the webs of said inverted channel member, and spaced tie plates connected adjacent their extremities to said center sill webs and to said inverted channel member webs inwardly of the ends of said inverted channel member for mutually joining all of said webs together.
2. In a car underframe including an inverted channel center sill having spaced apart webs, a bolster center filler comprising an inverted channel member having the webs and top portion thereof arranged within the center sill with the top portion directly connected to the center sill and the web portions thereof spaced from the center sill webs, spaced continuous tie plates directly connected to said inverted channel member webs inwardly of the ends of said inverted channel member and to the center sill webs and joining all of said webs together, and a base plate joining the lower portions of said tie plates together and extending outwardly substantially to the ends of said inverted channel member, said base plate extending substantially from end to end of said member and being secured to the lower portion of said inverted channel member.
3. In a car underframe including an inverted channel center sill having spaced apart webs, a bolster center filler comprising an inverted channel member having the webs and top portion thereof arranged within the center sill with the top portion directly connected to the center sill and the web portions thereof spaced from the center sill webs, spaced tie plates directly joining said inverted channel member webs together and extending outwardly therefrom for direct connection to the center sill webs, and a base plate joining the lower portions of said tie plates together and secured to the lower portion of the webs of said inverted channel member thereby forming a substantially closed box-section intermediate the center sill webs, said closed box-section being internally braced by means secured to the inverted channel member intermediate said

tie plates and so formed and arranged as to provide a guide for a king pin.

4. In a car underframe including an inverted channel center sill having spaced apart webs, a bolster center filler comprising an inverted channel member having the webs and top portion thereof arranged within the center sill with the top portion directly connected to the center sill and the web portions thereof spaced from the center sill webs, spaced tie plates directly joining said inverted channel member webs together and to the center sill webs, and a base plate joining the lower portions of said tie plates together and secured to the lower portion of the webs of said inverted channel member thereby forming a substantially closed box-section, said closed box-section being internally braced by M-shaped plates having their legs secured to the inverted channel member webs and their apices secured together to form a king pin guide.

5. As an article of manufacture a bolster center filler for car center sills having spaced apart webs and comprising short unsymmetrical Z bars having vertical webs and narrow flanges directed toward each other, flanged tie plates secured to the ends of the Z bar webs and having the flanges thereof located in outwardly spaced parallel relationship to the webs of the Z bars for attachment to the webs of the car center sills, and a base plate secured to the lower edges of said tie plates and the lower portions of the webs of the Z bars.

6. As an article of manufacture a bolster center filler for car center sills having spaced apart webs and comprising short unsymmetrical Z bars having vertical webs and narrow flanges directed toward each other, flanged tie plates secured to the ends of the Z bar webs and having the flanges thereof located in spaced parallel relationship to the webs of the Z bars, opposed M-shaped plates having their leg portions secured to the Z bar webs to form a king pin guide and brace, and a base plate bearing on the ends of said M-shaped plates and being secured to the lower portions of said tie plates and Z bar webs.

7. As an article of manufacture a bolster center filler for car center sills having spaced apart webs and comprising short unsymmetrical Z bars

having vertical webs and narrow flanges directed toward each other, tie plates extending across and secured to the ends of the Z bar webs to form a box shaped section, said tie plates extending beyond the webs and having their extremities flanged for attachment to the car center sills, and a base plate secured to the lower portions of said tie plates and Z bar webs and substantially closing said box shaped section, said base plate extending outwardly beyond the lower portions of the tie plates to provide flanges for the attachment of a car center bearing.

8. As an article of manufacture a bolster center filler for car center sills having spaced apart webs and comprising short unsymmetrical Z bars having vertical webs and narrow flanges directed toward each other, portions of the Z bar webs being cut away to provide web ends inset from the flange ends, spaced tie plates secured to the web ends and joining said Z bars together, said tie plates extending beyond said Z bar webs and being formed with outwardly directed flanges located in spaced parallel relationship to the webs of the Z bars, and a base plate secured to the lower edge portions of said tie plates and of said Z bar webs.

9. In a car underframe having an inverted channel form center sill with spaced apart webs and bolster diaphragms on the outer sides thereof all supported by a center bearing, a bolster center filler comprising an inverted channel form member having spaced webs and a top portion arranged within the center sill at the bolster zone and having the top portion directly bearing on the center sill top portion and the webs thereof spaced from the center sill webs, spaced tie plates located substantially in the plane of the bolster diaphragms and mutually connecting the center sill webs and the webs of the inverted channel form member, and a base plate mutually joining the lower portions of said tie plates and of said inverted channel form member, said base plate extending outwardly beyond the points of junction with said tie plates to provide flanges for the attachment of the center bearing.

JOHN CHRISTIANSEN.
